UNITED STATES PATENT OFFICE

2,364,053

CRUTCH

James Bourne, Mount Vernon, N. Y.

Application November 23, 1943, Serial No. 511,407

5 Claims. (Cl. 135—52)

This invention relates to crutches for the lame, and more particularly to means for cushioning shocks to the user of the crutch in cooperation with pivoting means to minimize other discomforts arising from the rubbing of the armpit on the saddle of the crutch.

An object of the invention is to provide a structure of this character that can be cheaply manufactured, and one in which the pivoting means will be widely spaced transversely to counteract undesirable twisting movements of the saddle tending to make the crutch unstable. Another object of the invention resides in a structure suitable for use as an attachment to existing crutches with rigid wooden saddles.

In carrying out the foregoing and other objects, this invention provides an improved construction in which the mounting of the saddle minimizes sliding of the same under the armpit when the body of the user is swinging through a stride.

Pivoting means heretofore proposed for this purpose have been applied at a single point in alignment with the vertical axis of the crutch and with the springs employed for cushioning the saddle. In such a construction twisting strains during use of the crutch are concentrated at this one point, and the parts tend to become rickety. In the present invention the pivoting means are spaced to a maximum extent on opposite sides of the aligned springs, providing for a rocking movement of the saddle forwardly and rearwardly as well as to a limited extent transversely, but without loss of stability with respect to pivotal movement of the saddle about the vertical axis of the crutch.

The invention will be more fully understood by reference being had to the accompanying drawing forming a part of this specification, and in which drawing,

Fig. 1 is a side elevation partly in section, of the upper end of a crutch with an embodiment of the invention shown applied thereto in the form of an attachment suitable for ordinary wooden saddle crutches.

Fig. 2 is a vertical transverse section taken on the line 2—2 of Fig. 1.

Fig. 3 is a section similar to Fig. 1 but illustrating a modified form of the invention, and,

Fig. 4 is a vertical section taken on the line 4—4 of Fig. 3.

In the drawing the fragmentary upper portion of a crutch 10 is shown having the usual wooden shoulder rest or head member 11, but which has been cut along the line 12—12 to provide a flat

surface 13. The dot and dash lines indicate the original outline of the member 11 before the cutting operation. The crutch 10 is now ready for the application of the attachment shown in Fig. 5 comprising a hollow saddle member 14 of suitable configuration, and having depending continuous end and side walls, the latter being indicated at 15. Member 14 is open at the bottom, and the top wall is shaped to correspond to the usual contour of the top of a crutch. It is preferably an aluminum casting having downwardly extending studs 16 for securing and centering a series of aligned springs 17 which may be frusto-conical as shown, and having their lower ends of increased diameter for engagement with the surface 13 when the attachment is applied to the crutch 10. The upper ends of the springs of lesser diameter may be secured to the studs 16 by a force fit, or in any other suitable manner. 10 The side walls 15 of member 14 are provided respectively with centrally located tabs 18 extending downwardly from the lower edge thereof, and have slots 19 therethrough. The attachment may be secured to the wooden member 11 in the desired manner by screws 20 which pass through the slots 19 and into the sides of said member. The saddle member 14 will then be free to move downwardly compressing the springs 17, and at the same time to rock on the pivots provided by the screws 20, and to rock to a limited extent transversely by reason of the slotted side walls.

It will now be apparent that as the body of a person using the crutch swings through a stride 35 there will be angular movement of the saddle member 14 about the central pivotal screws 20 while the springs 17 are partially compressed, and that such movement of the saddle will be relative to the crutch instead of to the armpit, the spaced pivotal points effectively maintaining the desirable alignment of the saddle and the head members during such movement.

Referring to Fig. 3, a hollow saddle member 25 may be molded from plastic material such as 45 Bakelite, with a suitably shaped top wall 26 to fit the armpit, and depending continuous end and side walls, the latter being indicated by the numeral 27, and with bosses 28 on the inner surface of the top wall 26. A head member 29 consists of a metal plate formed with side walls 30 having centrally located tabs 31 projecting upwardly from their lower edges, and having slots 32 therethrough, and bosses 33 extending upwardly. The member 29 has tubular bosses 34 formed to project downwardly for securing it to

the usual truss bars of a crutch, shown broken away at 35. A series of aligned springs 36 positioned between and by the aligned bosses 28 and 33, are of suitable shape such as the springs 11, and serve the same purpose.

Inserts 37 are molded in the side walls 27 of member 25, and are bent inwardly so that their inner surface will be flush with the inner surface of the walls 27. The inserts 37 are positioned centrally along the side walls so as to be opposite the tabs 31, and have openings 38 therethrough for the insertion of a bolt 39 which is of suitable length to reach across the saddle member 25. The side walls 27 have openings 40 leading inwardly to the inserts 37 so that the head of the bolt and a nut 41 on the opposite end may be contained therein without projecting beyond the outer surface of the walls. The shape of at least one of the openings 40 may conform to that of the nut 41 so that the latter will be held stationary while the bolt is being applied. The bolt 39 provides a pivotal connection for the two members, and in cooperation with the slots 32 provides for the rocking movement of the saddle member in the manner already described.

The foregoing description is merely illustrative and not intended as limiting the invention thereto.

I claim:

1. In a crutch having spring means interposed between its saddle member and head member, the combination therewith of side walls on one of said members fashioned to overlap the side walls of the other member, the said side walls of one of said members being slotted, and means for pivotally securing said members together through said slots for the purpose set forth.

2. An attachment for the head member of a crutch, comprising a hollow saddle member having centrally disposed vertical slots at opposite sides thereof for pivotally and slidably attaching said saddle member to the sides of said head member in overlapping relation thereto, and spring means mounted within the saddle member

between said slots for yieldably supporting the saddle member on the head member for the purpose set forth.

3. In a crutch having a hollow saddle member, and a head member secured to the truss bars of said crutch, and spring means interposed between said members, the combination therewith of means for flexibly securing said members together comprising centrally-slotted side walls on one of said members overlapping the side walls of the other member, and means for pivotally connecting the contiguous side walls of said members through said slots for the purpose set forth.

4. In a crutch having a hollow saddle member, and a head member secured to the truss bars of said crutch, and spring means interposed between said members, the combination therewith of means for flexibly securing said members together comprising centrally-slotted side walls on said saddle member overlapping the sides of said head member, and means for pivotally connecting the contiguous side walls of said members through said slots for the purpose set forth.

5. A resilient rocking head for a crutch comprising a hollow saddle member made of plastic material, and a metallic plate member for attachment to the truss bars of said crutch, and having side walls extending upwardly within said saddle member in juxtaposition to the side walls thereof, each of said walls of the plate member being provided with a centrally disposed vertical slot therethrough, said saddle member having a metallic insert molded in each of the side walls thereof opposite said slots and substantially flush with the inner surface of said walls, a bolt extending transversely through said inserts and said slots for pivotally and slidably connecting said members, the side walls of the saddle member having openings leading inwardly to said inserts to receive the opposite ends of said bolt, and spring means interposed between said saddle and plate members.

JAMES BOURNE.
